United States Patent Office

Des. 234,101
Patented Jan. 21, 1975

234,101

STOOL

Philip Robert Salmon, Mississauga, Ontario, Canada (485 Broadview Ave., Toronto, Ontario, Canada), and Hugh Campbell, Willowdale, Ontario, Canada (R.R. 1, Edwards, Ontario K0A 1V0, Canada)

Filed Apr. 23, 1973, Ser. No. 353,600

Term of patent 14 years

Int. Cl. D6—01

U.S. Cl. D6—26

FIG. 1

FIG. 2

FIG. 3

FIG. 4

FIG. 1 is a perspective view of a stool embodying our new design;

FIG. 2 is a plan view from the top of the stool illustrated in FIG. 1;

FIG. 3 is one side view of the stool illustrated in FIG. 1; and

FIG. 4 is a side view of the stool illustrated in FIG. 1 from the opposite side to that illustrated in FIG. 3.

We claim:

The ornamental design for a stool, substantially as shown.
